(57) **CLAIM**

The ornamental design for an armband for holding an electronic device, as shown and described.

DESCRIPTION

FIG. 1 is a bottom plan view of an armband for holding an electronic device showing our new design;

FIG. 2 is a top plan view thereof;

FIG. 3 is a right elevation view thereof;

FIG. 4 is a left elevation view thereof;

FIG. 5 is a front elevation view thereof; and,

FIG. 6 is a rear elevation view.

The broken lines depict environment and form no part of the claimed design.
